UNITED STATES PATENT OFFICE.

EPHRAIM S. PEASE, OF BUFFALO, NEW YORK.

DESIGN FOR AN ICELESS REFRIGERANT.

58,501.

Specification for Design.

Patented July 26, 1921.

Application filed July 6, 1920. Serial No. 394,364. Term of patent 7 years.

To all whom it may concern:

Be it known that I, EPHRAIM S. PEASE, a citizen of the United States, residing at Buffalo, in the county of Erie and State of New York, have invented a new, original, and ornamental Design for an Iceless Refrigerant, of which the following is a specification, reference being had to the accompanying drawing, forming a part thereof.

The accompanying drawing is a perspective view of an iceless refrigerant embodying the invention.

The refrigerant includes a bowl or container A having legs or feet *a* and a cover B adapted to rest on the upper edge of the bowl.

I claim:

The ornamental design of an iceless refrigerant, as shown and described

EPHRAIM S. PEASE.

Witness:

F. E. PROCHNOW.
